(57) **CLAIM**

We claim the ornamental design for an interface dial for small appliances, as shown and described.

DESCRIPTION

FIG. 1 is a front view of the interface dial for small appliances of a first embodiment, showing our new design. FIG. 2 is a front perspective view of the interface dial for small appliances of FIG. 1.

FIG. 3 is a side view of the interface dial for small appliances of FIG. 1, the opposite side being a mirror image thereof.

FIG. 4 is a front perspective view of the interface dial for small appliances of FIG. 1, in an environment of use.

FIG. 5 is a front perspective view of the interface dial for small appliances of FIG. 1, in an alternate environment of use.

FIG. 6 is a front perspective view of the interface dial for small appliances of a second embodiment, showing our new design; and,

(Continued)

FIG. 7 is a front perspective view of the interface dial for small appliances of FIG. 6, in an environment of use. The broken lines included in the drawings represent environment and portions of the article and form no part of the claimed design.
